UNITED STATES PATENT OFFICE

92,784

DESIGN FOR A WING COLLAR

Martinus Van Gelder, Philadelphia, Pa.

Application May 8, 1934, Serial No. 51,718

Term of patent 14 years

To all whom it may concern:

Be it known that MARTINUS VAN GELDER, a subject of the Queen of Holland and a resident of Philadelphia, in the county of Philadelphia and State of Pennsylvania, has invented a new, original, and ornamental Design for a Wing Collar, of which the following is a specification, reference being had to the accompanying drawing, forming part hereof, in which:

Fig. 1 is a plan view of the collar in the flat condition.

Fig. 2 is a front perspective view of the collar when it is in use.

Fig. 3 is a side elevation of Fig. 2.

I claim:

The ornamental design for a wing collar as shown.

In testimony whereof, I affix my signature.

MARTINUS VAN GELDER.
